UNITED STATES PATENT OFFICE.

GEORGE W. SAVAGE, OF NORWALK, OHIO.

RAIL-FASTENING.

SPECIFICATION forming part of Letters Patent No. 595,656, dated December 14, 1897.

Application filed August 7, 1897. Serial No. 647,403. (No model.)

To all whom it may concern:

Be it known that I, GEORGE W. SAVAGE, a citizen of the United States, residing at Norwalk, in the county of Huron and State of Ohio, have invented certain new and useful Improvements in Rail-Fastenings; and I do hereby declare the following to be a full, clear, and exact description of the invention, such as will enable others skilled in the art to 10 which it appertains to make and use the same.

My invention relates to improvements in rail-fastenings, being particularly designed for fastening railway-rails to metal ties, the object being to secure increased simplicity of 15 construction, ease of application, and durability and efficiency in use.

To these ends the invention consists in the novel features of construction and combination of parts hereinafter described, and specifically pointed out in the claims.

In the drawings, Figure 1 is a plan view of a tie having rails secured thereto by my improved fastening. Fig. 2 is a vertical section through the tie and rail, showing in side elevation my fastening device in place. Fig. 3 is a side view of a rail secured to a tie by my improved fastening. Fig. 4 is a detached view of the holding-stud. Fig. 5 is a detached view of the locking-wedge, and Fig. 6 is a view of 30 a somewhat modified form of wedge.

The great superiority of metal ties over wooden ones has long been recognized, owing in part to the fact that experience has shown that it is impossible to permanently secure 35 metal rails to wooden ties. The rails wear the wooden ties where they rest upon them, and the enormous strain upon the rails causes the spikes or other fastenings to wear in the wood, both causes giving rise to the speedy 40 loosening of the rail attachment to the ties. Redriving of the spikes, &c., is of but little avail, as the redriving of the spikes wears their seat in the wood and they have only a diminished holding power.

45 In the use of metal ties there is found no difficulty in effecting a permanently rigid fastening of the rail to the tie, but it has not been found easy to provide a fastening which is at once permanently secure, not complicated, durable, and capable of ready removal and replacement, so as to admit of prompt

repairs when needed, as in case of a rail breaking, &c. This it is my aim to supply.

A represents the rail, and B the tie, which may be of any pattern.

55 b is a lip or hook struck up from the top of the tie and under which one flange a of the rail may be placed, as seen at the right-hand end of Fig. 1, although it may be preferable to use my improved fastening for both 60 sides of the rail, as seen at the left-hand end of the same figure.

C represents a hook-stud formed with a strong hook c, a body c², and a head c³, preferably provided with downward-extending 65 lips or lugs c⁴, for a purpose presently to be described. In use the stud C is seated in an opening b² in the tie, which the body c² of the stud substantially fills, the rail-flange a bearing against the body of the stud and a wedge 70 D being driven under the head of the bolt to cause the hook c to bear firmly against the under side of the tie. The wedge D is formed with two legs d d², one of which tapers to a thin end and the other of which is preferably 75 blunt to enable the wedge to be driven out when the rail is to be removed.

When the wedge is driven under the head of the stud, the lips c⁴ extend down outside of the wedge, as seen in Figs. 2 and 3, which 80 prevents the wedge from spreading and becoming loose. One leg of the wedge is driven between the flange a and the head c³, helping to hold down the rail, and the other is driven between the head c³ and the tie, and 85 this leg, by preventing the head c³ from approaching the top of the tie, absolutely prevents the removal or loosening of the stud while the wedge is in place. After the wedge is driven home the thin end of one leg is bent 90 down over the corner of the tie, as seen in Fig. 2, which prevents the loosening or removal of the wedge until the downbent end is bent up again by a suitable tool made for the purpose. The bending down of the wedge 95 end tends to draw the wedge still tighter, whereas if it were bent upward it would tend to loosen it.

When the rail is to be removed, as for replacing a broken or defective rail by a new 100 one, the downbent end of the wedge is straightened up and the wedge is driven out by blows

on the end of the blunt leg, whereupon the stud can be easily turned away from the rail and unhooked and removed, leaving the rail free. When the new rail is put in place, the 5 same fastening can be speedily replaced as before without waste, the wedge being malleable at the tip and preferably made of steel.

When the ties are made with the hooked lugs *b* for the inner side of the rail, the lugs 10 are spaced to bring the rail to gage when abutted against them, and the holes for the studs *C* are likewise punched at the proper distance, so that the insertion of the studs will bring the rail to gage.

15 By forming the wedge of the shape shown by *D*² in Fig. 6 any tendency of the wedge to spread in driving is avoided.

The advantages of my improved fastening are the absence of threaded parts, which are 20 very objectionable in railroad-work; the simplicity and small number of parts required; their capability of quick application, of ready removal, replacement, and repeated use of the same parts; their strength and durability; 25 the impossibility of their wearing, jarring, or pounding loose, as most fastening devices now in use are liable to; the great difficulty of unlawful tampering with them, to which threaded parts are very liable, and, finally, 30 the work is all done from above and there is no need to get at the under side of the tie.

What I claim as my invention is—

1. In a rail-fastening the combination with the rail and perforated tie, of headed studs 35 passing through said perforations and bearing against the rail-flange, a hook on said stud engaging the under side of the tie, and a wedge of substantially **U** shape driven under

the head of the stud, one leg of the wedge passing each side of the shank of the stud, 40 and one of said legs being clenched, substantially as described.

2. In a rail-fastening the combination with the rail and perforated tie having hooked lugs against which the rail-flange abuts, of headed 45 studs engaging the perforations of the tie and having a hooked end which engages the under side of the tie, and a wedge of substantially **U** shape driven under the head of the stud, one leg of the wedge passing on each side of the 50 shank of the stud, and one of said legs being clenched, substantially as described.

3. In a rail-fastening the combination with the rail and the perforated tie having hooked lugs against which the rail-flange abuts, of 55 headed studs engaging the perforations of the tie and having a hooked end which engages the under side of the tie, and a wedge of substantially **U** shape driven under the head of the stud, one leg of the wedge passing between 60 the head of the stud and the rail-flange and the other leg passing on the opposite side of the shank of the stud and being clenched, substantially as described.

4. In combination with the rail and perforated tie, the hooked stud having a head provided with downturned lips, and a double wedge having its legs adapted to pass between the body of the stud and said lips, substantially as described. 65

In testimony whereof I hereto affix my signature in presence of two witnesses.

GEORGE W. SAVAGE.
